JOHN HOLTZMAN, OF NEW YORK, N. Y., ASSIGNOR OF ONE-HALF TO BENJAMIN ROMAN,
OF NEW YORK, N. Y.

DEVICE FOR PREVENTING THEFT OR UNAUTHORIZED USE OF AUTOMOBILES.

Application filed September 15, 1921. Serial No. 500,869.

This invention relates to devices that are intended to prevent the theft or unauthorized use of automobiles, and particularly to the type which is attached to one of the running 5 wheels of the automobile so as to interfere in some manner with its normal operation.

The principal object of my invention is to provide an efficient and improved device for the above purpose which will remedy many 10 of the disadvantages and defects found in and inherent to the devices heretofore utilized or proposed.

Other objects and advantages will herein-after appear.

15 In the accompanying drawings,—

Fig. 1 shows a front elevation of the device.

Fig. 2 is a plan view of the device shown in Fig. 1.

20 Figs. 3, 4, and 5 show views of modifications of parts of the improvements constituting this invention.

Against the inner surfaces 1 of the diametrically opposite sides 2 of the felly 3 of the automobile wheel 4 are located heads or members 5, 6, parts from which extend as legs 7, 8 to the ground 9. Said legs are disposed downwardly obliquely, and in opposite directions away from the axis of the wheel 4. The members 5, 6 are provided with lugs 10, into which 25 are threaded the legs 11 of L-shaped bolts 12, 13, respectively. To the leg 14 of bolt 12 is threaded the bossed end 15 of an arm 16, and to the leg 14 of bolt 13 is threaded the bossed end 17 of an arm 18. The opposite end 19 of 30 the arm 18 is formed as a block 20, to which is hinged at 21 the extremity 22 of the arm 16, and an arm 23, forming part of the block 20 and thereby constituting an extension of the arm 18, extends from said block over to the 35 end 15 of the arm 16, whereat the bossed end 24 of the arm 23 registers with the end 15. Within the arm-end 24 is encased a lock barrel, the lock bolt 25 of which enters into a keeper-opening 26 provided in the arm-end 40 15, whereby by manipulation of the key 27 the arm-end 24 may be locked to and unlocked from the arm-end 15. The arms 16, 18, can be normally swung relatively to each other about the hinge 21, whereby the entire device may 45 be readily detached from the wheel 4 by merely unlocking the arm ends 24, 15, and drawing the arm 23 away from the arm 16, which action causes the arms 16, 18 to swing toward each other and the members 5, 6 to move 50 55 toward each other and to entirely clear the di- ametrically opposite portions 2 of the felly 3. As the automobile-wheels 4 vary to some extent in their dimensions, provision is made in this device wherewith it may be adjusted to accurately fit to any wheel, so that when the 60 device is attached to any wheel it will be fully and efficiently operative thereon to carry out its function. When it is desired to attach this device to any wheel therefore, the bolt legs 14 are first threaded in the arm-ends 15, 17 to 65 such extent that when the members 5, 6 are in operative position on the felly 3 and the device is in attached state the block 20 will bear against the hub-cap 28, and then the members 5, 6 are threaded along the bolt-legs 11 to such 70 position that when in operative position said members will bear forcibly against the surfaces 1 of the sides 2 of the felly 3. After the device has been thus once adjusted, it may be attached to the wheel 4 whenever required, by 75 merely passing the members 5, 6 against the rim-portions 2 in the position shown, then swinging the arm 23 toward the arm 16, and then locking the arm-ends 24, 15 to each other with the key 27, whereupon the device be- 80 comes securely fastened in locked state to the opposite sides of the wheel felly 3, with its legs 7, 8 resting upon the ground. If desired the adjustment of the bolt-legs 14 in the arm-ends 15, 17 may be made so as to cause the pro- 85 jections 29 of the members 5, 6 to bear forcibly against the felly 3, and the block 20 to bear forcibly against the hub-cap 28, upon the lock- 90 ing of the levers or arms 23, 16, in which case the device can be secured to the wheel-hub and the rear side of the felly 3 in addition to being secured to the diametrically opposite sides 2 of the rim.

When the device is thus fastened in the operative device shown, any attempt at stealing or unauthorized use of the automobile will be frustrated, because the wheel will be locked against any possible rotation by the legs 7, 8 standing upon the ground; and this locking of the wheel as well as the abutment of the legs 100 against the ground will prevent any propul- 95 sion or steering of the automobile, either by its own power or by means of towing away the machine, as is frequently resorted to by thieves at the present time. Should the thief 105 undertake to remove the wheel 4, from its axle, with the device attached thereto, and then substitute another wheel in its place, the same would be frustrated by the block 20 being locked against the hub-cap 28, without the un- 110

threading and removal of which he could not possibly remove the wheel 4.

To the leg 8 is pivoted at 30 a lever 31 which carries a knife 32. If attempt is made to tow 5 away the machine, in spite of the difficulties produced by the device, the abutment of the lever 31 against the ground will swing the lever toward the left and cause the knife 32 to puncture and deflate the tire 33. The load 10 of the machine will therewith bear directly upon the device and its legs 8, and propulsion or towing of the automobile will be thereby further prevented.

According to the modification shown in 15 Fig. 3, the device comprises a pair of curved arms 34, 35, that have their ends 36 hinged to each other at 37, which hinge is located near to the inner side of the felly 3. Said arms are provided with shoulders 38, adja- 20 cent to the hinge 37, which embrace the felly 3, and the arms extend from the hinge around the tire 33 and meet each other at 39, where their ends, formed as blocks 40, 41, are locked to each other by means of the key 42. 25 Upon one of the arm-ends 36 is formed a lug 43, in which threads a shank 44 having at its extremity a fork 45 which is adapted to embrace the hub 46 of the wheel 4. When this device is first attached to the automobile- 30 wheel 4, the shank 44 is adjusted in the lug 43 to such a position that when the device is in locked state the fork 45 will bear against the hub 46 and the shoulders 38 will bear against the felly 3, in which manner the de- 35 vice becomes securely attached to the wheel upon the locking thereof with the key 42. To detach the device, it merely requires un- locking with the key 42, then swinging the arms 34, 35 about the hinge 37, which releases 40 the fork 45 from the hub 46 and the shoulders 38 from the felly 3, and then withdrawing the device from the wheel 4. A set-screw 47 may be threaded in one of the shoulders to 45 adjust it to fit to felly 3 of any width.

Should attempt be made to run the machine when the device of Fig. 3 is attached to its wheel, the same would be frustrated by abutment of its arm-ends 40, 41 against the ground, which would prevent the free rotation of the wheel 4. In the arm-end 40 is threaded a bushing 48 having a bore 49, through which passes a knife 50 slidable toward the tire 33. Should attempt be made to ride the machine, in spite of the difficulties produced by this device, the abutment of the terminal 51 of the knife against the ground would cause it to puncture and deflate the tire 33, which occurrence would further prevent the propulsion or towing of the machine. 55 Should the thief undertake to dislocate the device, by deliberately deflating the tire and then turning the device therearound to offset the arm-ends 40, 41 and reinflating the tire, the same would be frustrated by the attachment of the fork 45 of the device to the hub 60 65

46. To prevent removal of the wheel 4, when this device is attached thereto, a chain 52 secured to an ear 55 forming part of the arm 34, and the opposite end of said chain is secured to a collar 54 at 53, which collar consists of two halves 56 that pass around the wheel axle 57, and are hinged to each other at 58, and their ends 59 are locked to each other by means of the key 60.

According to the modification shown in 75 Figs. 4 and 5, the device comprises a member 61, which embraces the felly 3 and part of the tire 33, and a leg 62 forming part of said member extends therefrom to any length or distance desired beyond the periphery of the 80 tire. Said member is provided with a lug 63 forming part thereof, through a bore 64 of which passes slidably a rod 65 having at its terminal a fork 66, to which it is secured by means of the thread 67, which fork embraces 85 the hub 46. Rotation of the rod 65 is prevented by means of a pin 68 secured thereto projecting into a slot 69 formed in the bore 64. The end 70 of the rod 65 is provided with a spring 72 upon its extremity, which 90 spring bears constantly against the rod and also against a cap 73 which threads into the bore 64, whereby this spring constantly presses against said rod and forces it outwardly. Upon the member 61 and lug 63 95 is formed as a part thereof a casing 74, in which is mounted the usual lock-barrel 75, secured to the casing by means of a screw 76. The usual rotatable flat lock-bar 77 projecting from the barrel 75 passes into an opening 78 formed in a cylindrical bolt 79 which is rotatably mounted in the casing 74, by means of said passage of the bar 77 thereinto and a projecting stud 80 thereof being mounted in 100 a bearing 81 formed in the casing. Said bolt 79 is provided with a slot 82 having an angular or slant bottom-wall 83, and a disk 84 is located in said slot, with its periphery bearing against the slot-wall 83 of the bolt 79 and against the rod end 70 located within the bore 64. The casing 74 is provided with an internal guide-channel 85, so that when the bolt 79 is rotated, by manipulation of the key 86, said channel guides the disk 84 and permits it to be retained within the slot 82 of the bolt while the latter is rotated, whereby the disk 84 is rotated together with the bolt. When the bolt 79 is thrown into an inoperative condition by the key 86, it carries the disk 84 away from the rod 65 and permits the rod to be slid freely through the bore 64 in either direction, inwardly or outwardly, and when said bolt is disposed to a locked operative position it throws the disk 84 into the position shown in contact with the rod 105 110 115 120 125 130 135 65 70 75 80 85 90 95 100 105 110 115 120 125 130 135

- rod to any extent inwardly or toward the right, the same is absolutely prevented by the rod 65 bearing against the disk 84 and binding it between the rod and the slot-wall 83 of the bolt 79. A spring 87 located in a recess 88 in the casing 74 bears against the disk 84 and thus facilitates the binding action thereof between the bolt-wall 83 and the rod 65, whereby any back-lash of said rod 10 toward the right is prevented. All that is necessary to attach this device to the wheel 4, is to first slide the rod 65 inwardly as far as it will go, then, while holding the rod in this position, to grasp the member 61 with the other hand and slip it over the rim 3 in the position shown, and then, while still holding said member, to release the rod 65, whereupon the spring 72 will automatically force the rod 65 outwardly and cause its fork 66 20 to bear pressingly against the wheel-hub 46. The key 86 may be then turned, and withdrawn, to throw the disk 84 into the locked position shown, which will securely lock the device in place. To detach this device, it merely requires unlocking it with the key 86, then shifting the rod 65 inwardly to cause its fork 66 to clear the hub 46, and then withdrawing the device from the wheel. The leg 62 of this device may be made long to 30 about the extent of the leg 8 in Fig. 1, and two of these devices may be attached to the wheel-rim, one at each side of the wheel-hub and in contact with the ground, so as to carry out the same function as that described in connection with the legs 8, Fig. 1. If desired, the projection 89 of fork 67 may be itself formed as a fork 90, which passes around the sleeve-portion 91 of the wheel-hub, and thereby adds further difficulty to any attempt 40 at dislocation of the device by a thief. An opening 76^a in the lug 63 permits a screw driver to be passed therethrough for threading the screw 76 in place during assemblage of the device.
- If desired, the leg 62 of this device may be made to have a casing 92 formed thereon, wherein there is located a usual bell-alarm mechanism operated by a spring motor, not shown, on the spring-shaft 93 of which there 50 is keyed an escapement-wheel 94 having a series of notches 95. In the casing 92 is provided an opening 96, through which may be passed a detent 97 which enters either of the notches 95. Said detent is slidably in a cylinder 98 having a spring 99 therein and a shoe 100 formed at its terminal. The device may be attached to the wheel 4 in the position shown in Fig. 4, and, after winding the spring-motor of the alarm-mechanism with 60 a key in the usual manner, the detent 97 with the cylinder 98 may be set up in the position shown, the spring 99 serving to hold the detent in place and to adjust the detent with the cylinder 99 to any position at which the casing with its opening 96 may chance to be 70 disposed in the attachment of the device. It will be evident that any attempt thereafter to tow the car or to in any manner rotate the wheel for the purpose of tampering with the device, the detent 97 will release the escapement-wheel 94 and thereby set off the alarm, which would cause detection of the attempted theft and thereby add further to the utility of the device. Preferably, an arm 101 extends from the detent 97 over to the keyhole 75 of the device, whereat it terminates in a plate 102, which covers said keyhole, whereby if attempt is made to pick the lock it would require removal of plate 102 and hence would cause dislocation of the detent 97, which 80 would in turn set off the alarm.
- It will be evident to those versed in this art, from an examination of this invention, that in addition to the various advantages above pointed out, these improvements will 85 furthermore remedy many of the serious disadvantages and defects that are known to exist in the devices heretofore known.
- Variations may be resorted to within the scope of the invention, and portions of the 90 improvements may be used without others.
- Having thus described my invention, I claim:
1. An anti-theft device for automobiles having means projecting beyond the periphery of the automobile wheel, means to secure the device to the felly of said wheel, means to secure the device to the hub of said wheel, means to move said securing means parallelly to each other toward and away 95 from each other for fitting the device to said wheel, and key operated mechanism to lock said securing means to each other.
  2. An anti-theft device for automobiles having means projecting beyond the periphery of the automobile wheel, means to secure the device to the felly of said wheel, means to secure the device to the hub of said wheel, means to move said securing means 100 telescopically toward and away from each other for fitting the device to said wheel, and key operated mechanism to lock said securing means to each other.
  3. An anti-theft device for automobiles having means projecting beyond the periphery of the automobile wheel, a member joined to said means adapted to grasp the felly of said wheel on three sides, a member adapted to grasp the hub of said wheel on three sides, and key operated mechanism to 110 lock said members to each other.
  4. An anti-theft device for automobiles having means to secure it to the felly of the automobile wheel, means to secure it to the hub of the wheel, said means being movable 115 toward and away from each other for adjusting both of said means for attachment of the device to the wheel, and key operated mechanism to lock said two means to each other 120 in any adjusted position.

5. A device of the class described having means to secure it to the felly of the automobile wheel, means to secure it to the hub of the wheel, said means being movable toward and away from each other for adjusting both of said means for attachment of the device to the wheel, locking mechanism including a binding surface, a movable member adapted to bind against said surface, said mechanism when in locked state disposing said member in the path of one of said means, and said last means causing said member to bind it between it and said surface to prevent relative movement of said means toward each other.

6. A device of the class described having means projecting beyond the periphery of the automobile wheel, a member adapted to grasp the felly of said wheel, a member adapted to grasp the hub of said wheel, spring means tending to force said members away from each other, and means to secure said members to each other.

7. An anti-theft device for automobiles having means projecting beyond the periphery of the automobile wheel, a member adapted to grasp the felly of said wheel, a member adapted to grasp the hub of said wheel, means tending to force said members away from each other, and key operated mechanism to lock said members to each other while locking the member in one direction.

8. A device of the class described having means to secure it to the felly of the automobile wheel, means to secure it to the hub of the wheel, said means being movable toward and away from each other for adjusting both of said means for attachment of the device to the wheel, locking mechanism including a movable member having a binding surface, said mechanism when in locked state disposing said member in the path of one of said

means, and said last means causing said member to bind it to prevent relative movement of said means toward each other.

9. A device of the class described having means to secure it to the felly of the automobile wheel, means to secure it to the hub of the wheel, said means being movable parallelly to and toward and away from each other for adjusting both of said means for attachment of the device to the wheel, and means to secure said two means to each other in adjusted position.

10. A theft prevention device comprising a pair of yoked members adapted to be mounted upon an automobile wheel, one of said members adapted to engage the felly of the wheel, said members being slideable longitudinally relatively to each other for adjustment, and key operated mechanism to lock said members to each other at any point.

11. A theft prevention device comprising a pair of members adapted to be mounted upon an automobile wheel, one of said members adapted to engage the felly of the wheel, said members being slideable longitudinally relatively to each other for adjustment, and key operated mechanism to lock said members to each other at any adjusted position.

12. The combination of a key operated locking mechanism, a member slideable adjacent to said mechanism in opposite directions, means to lock said member at any point by the operation of the key against movement in one direction, and said mechanism permitting movement of said member in an opposite direction while locking the member in the one direction.

Signed at the city of New York, in the county of New York, and State of New York, this 14th day of September, A. D., 1921.

JOHN HOLTZMAN.
